UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed September 23, 1925. Serial No. 57,986.

This invention relates to internal combustion engines and particularly to ignition means therefor.

It is well-known that it is desirable in an internal combustion engine to have a plurality of simultaneous sparks at several spaced points in the combustion chamber because by so doing there is a more uniform firing of the complete charge and what is known as "detonation" does not result. It is comparatively easy to provide two spark plugs per cylinder for an engine but to provide additional plugs and have them fire simultaneously presents many difficulties.

15 It is one of the objects of the present invention to provide means for simulating the effect of two spark plugs by the use of a single plug so that two plugs may be used in an engine cylinder with the effect of or 20 with better effect than four spark plugs.

Another object of the invention is to provide an internal combustion engine with ignition means in which a single spark plug is connected with the combustion chamber 25 by a plurality of separate mixture paths.

Another object of the invention is to provide means whereby the effect of a spark plug ignition is carried to separated points in the combustion chamber of an internal 29 combustion engine.

Another object of the invention is to provide an ignition recess in the piston whereby the inertia effect will insure the mixture reaching the spark plug.

35 Another object of the invention is to provide an engine piston with diverging passages through which the mixture is ignited.

Other objects of the invention will appear from the following description taken 40 in connection with the drawing which forms a part of this specification, and in which:

Fig. 1 is a vertical longitudinal section through a cylinder and piston of an internal combustion engine embodying the invention, 45 the section being substantially on the line 1-1 of Fig. 2;

Fig. 2 is a transverse section substantially on the line 2-2 of Figure 1; and

Fig. 3 is a section substantially on the line 50 3-3 of Fig. 1.

Referring to the drawing, 10 indicates the cylinder barrel of an internal combustion engine and 11 is the water jacket surrounding the cylinder. At its upper end the cylinder 10 is formed with a combustion

space or chamber 12 and with inlet and outlet ports 13 and 14 respectively. An inlet valve 15 and an outlet valve 16 are provided for these ports.

Sliding in the cylinder 10 is a piston 17 60 having a suitable boss 18 for the piston pin and for connection with the connecting rod, not shown. The piston is shown at the upper end of its stroke and in this position it forms the lower wall of the combustion 65 chamber 12. In the well-known four stroke cycle engine the exhaust valve will be open and the inlet valve closed when this upper position of the piston is at the end of the exhaust stroke, and this is the position in 70 which the parts are shown, the exhaust valve 16 being open. When the piston returns on its next up-stroke, which would be the compression stroke, both of the valves would be closed and the charge would be ready for 75 firing in the combustion chamber.

Two spark plugs 19 are shown mounted in opposite sides of the cylinder 10 and with their ignition points 20 in close proximity to the inner cylinder wall. These spark 80 plugs are so positioned that they are overrun by the piston on its up-stroke as shown in the drawing, so that they cannot communicate with the combustion chamber when the piston is in that position except through 85 passages or recesses provided in the piston itself or through some similar means. As shown, the piston 17 is formed with two diverging passages or conduits 21 for each of the spark plugs 19. The passages 21 meet 90 at their lower ends where a recess 22 is formed in the piston. As the piston moves downwardly on the intake stroke, the inertia of the gases causes most of the burnt gas to be withdrawn from the passages 21 and 95 recesses 22, and on the compression stroke the movement of the piston causes mixture to flow into and be compressed in said passages and recesses.

Each of the recesses is in communication 100 with the ignition points 20 of the spark plugs when the piston is at or near the top of its stroke as shown. The upper ends of the passages 21 extend through the upper wall of the piston and the four passages illustrated have their upper ends substantially equally spaced in the top of the piston, as particularly shown in Fig. 3. Thus, if the upper ends of these passages 21 were 105 ignition plugs, they would, if operated si- 110

multaneously, fire the charge in the combustion space to the best effect. In effect that is what happens by reason of the fact that upon the compression stroke some of the 5 mixture in the combustion chamber will be compressed in the passages 21 and the two spark plugs 19 will fire that mixture in the recesses 22. This firing of the mixture will be simultaneously communicated to the mixture 10 in the chamber 12 through the four passages 21 and as the upper ends of those passages are relatively spaced in the combustion chamber the firing of the mixture therein will be uniformly propagated from the four points and no detonation will result, but rather the greatest power will be 15 obtained from the charge.

While I have herein described in some detail a specific embodiment of my invention, which I deem to be new and advantageous and may specifically claim, I do not desire it to be understood that my invention is limited to the exact details of the construction, as it will be apparent that changes 20 may be made therein without departing from the spirit or scope of my invention.

Having thus described the invention, what is claimed and desired to be secured by Letters Patent, is:

- 30 1. In an internal combustion engine, the combination of a cylinder forming a combustion chamber, a piston, a spark plug, and means in the piston forming two separate paths for the mixture between the chamber and the spark plug.
- 35 2. A piston formed with two separate diverging ignition passages therein.
3. A piston having two separate ignition 40 passages extending and diverging from the side wall to the top.

4. A piston having two ignition passages extending from the side wall to the top, said passages being joined at the side wall and diverging upwardly therefrom.

5. A piston having an ignition recess in 45 its side and having two separate ignition passages from the recess to the top of the piston.

6. A piston having an ignition recess in its side and having two separate ignition 50 passages diverging upwardly from the recess to the top of the piston.

7. A piston having ignition recesses in opposite sides and having two separate ignition 55 passages from each of said recesses to spaced points in the top of the piston.

8. In an internal combustion engine, the combination of a cylinder forming a combustion chamber and having a spark plug in its side, and a piston in the cylinder adapted 60 to over-run the spark plug, said piston having a plurality of separate ignition passages formed therein and extending from the spark plug to the combustion chamber when the piston is at the top of its stroke. 65

9. In an internal combustion engine, the combination of a cylinder, spark plugs in opposite sides of the cylinder, and means in the piston forming a plurality of paths from each of said plugs to separated points in the 70 cylinder.

10. In an internal combustion engine, the combination of a combustion chamber, a piston, a spark plug, and means in the piston forming a recess communicating with 75 said spark plug and so arranged that gas is drawn from and caused to flow into said recess by inertia forces as the engine operates.

In testimony whereof I affix my signature.

LIONEL M. WOOLSON.
